UNITED STATES PATENT OFFICE.

HALSEY W. TAYLOR, OF WARREN, OHIO.

DESIGN FOR A BUBBLING-HEAD FOR DRINKING-FOUNTAINS.

51,563.

Specification for Design. Patented Dec. 11, 1917.

Application filed August 20, 1917. Serial No. 187,258. Term of patent 7 years.

To all whom it may concern:

Be it known that I, HALSEY W. TAYLOR, a citizen of the United States, residing at Warren, in the county of Trumbull and State of Ohio, have invented a new, original, and ornamental Design for a Bubbling-Head for a Drinking-Fountain, of which the following is a specification, reference being had to the accompanying drawing, forming part thereof.

Figure 1 is a top plan view and Fig. 2 is a side view of a bubbling head for drinking fountains, showing my new design.

I claim:

The ornamental design for a bubbling head for a drinking fountain, as shown.

HALSEY W. TAYLOR.
